PIPE WRENCH

Joseph Slizus, Seattle, Wash.

Application March 23, 1932. Serial No. 600,783

1 Claim. (Cl. 81—99)

This invention relates to wrenches and its general object is to provide a pipe wrench that is automatic in its action which is accomplished merely by moving the handle in one direction 5 to move the jaws in gripping position, while movement of the handle in an opposite direction will release the same with the result the wrench can be used on various sizes of pipe and the like and in places inaccessible to pipe wrenches now 10 generally employed.

A further object of the invention is to provide a pipe wrench that includes a movable jaw that is spring pressed to retain the same in normal position, and the shank of the movable 15 jaw is curved in a manner whereby the jaws cooperate to insure a positive gripping action.

Another object of the invention is to provide a pipe wrench of the character set forth, that is simple in construction, inexpensive to manufacture and extremely efficient in operation and 20 service.

This invention also consists in certain other features of construction and in the combination and arrangement of the several parts, to be 25 hereinafter fully described, illustrated in the accompanying drawing and specifically pointed out in the appended claim.

In describing my invention in detail, reference will be had to the accompanying drawing wherein like characters denote like or corresponding 30 parts throughout the several views, and in which:

Figure 1 is a top plan view of my wrench in use.

Figure 2 is a side elevation with the parts in 35 normal position.

Figure 3 is a sectional view taken approximately on line 3—3 of Figure 1, looking in the direction of the arrows.

Figure 4 is a detail view of the movable jaw member.

Figure 5 is a similar view of the spring for the 40 movable jaw member.

Referring to the drawing in detail, the reference numeral 1 indicates the handle of my wrench which has formed therewith and extending from one end thereof a pair of spaced parallel arms 2 which constitute the stationary 45 jaw member as will be apparent.

The arms incline slightly upwardly from 50 their connection with the handle 1 and are provided with arcuate faces having teeth 3 extending the entire length thereof as clearly shown in Figures 2 and 3. These teeth are directed at an inclination toward the handle,

and at the juncture of the arms with the handle, I provide a recess 4 for the purpose of receiving one of the ends of a leaf spring 5 that is secured therein through the instrumentality of a screw bolt 6. The leaf spring is directed 50 upwardly toward the outer end of the arms 2 for a purpose which will be presently apparent.

The movable jaw member for my wrench includes a shank 7 provided with an opening arranged adjacent one end thereof for the purpose of receiving a pivot pin 8 to pivotally secure the movable jaw member to the stationary jaw member, with the shank mounted for 65 slideable movement between the arms of the stationary jaw member as shown. Formed with 70 the opposite end of the shank 7 is a jaw 9 that is provided with a rounded outer surface and has formed with its inner surface teeth 10 that are directed in a direction opposite from that of the teeth 3. From the point of juncture of 75 the jaw 9 with its shank 7, it will be noted that the toothed surface thereof is substantially flat for a portion of its length but the outer end of the toothed surface is directed upwardly.

The shank is curved to a slight degree from 80 its connection with the jaw 9, and to a greater degree toward the pivot point thereof, and due to this curvature, it will be apparent that the toothed surface of the jaw 9 is disposed with respect to the toothed surface of the stationary 85 jaw member so as to insure positive gripping action or cooperation between the respective jaws at all times regardless of the size of pipe or object worked upon.

The movable jaw member is normally retained in open position through the instrumentality of the leaf spring 5 which is provided with a slot 11 to receive the screw bolts 6 whereby the leaf spring can be adjusted, and the free end of the leaf spring is rolled upon itself as 90 at 12 for engagement with the curved upper 95 surface of the shank. By employing the rolled abutting end for the leaf spring, it will be apparent that very little friction will be present 100 between the free end of the leaf spring and the shank, yet at the same time the leaf spring will act to hold the movable jaw member in open position as shown in Figure 2. Arranged in the path of the shank of the movable jaw member is a pin 13 so as to limit the forward movement of the movable jaw member.

From the above description and disclosure of the drawing, it will be obvious that I have provided a wrench that is primarily designed 105 for work upon pipes and the like and by em- 110

ploying the particular shape shank 7, particular shape jaw 9, as well as the particular shape stationary jaw, my wrench is capable of a positive gripping engagement and is likewise capable 5 of being used in places inaccessible to wrenches now generally employed. The leaf spring holds the movable jaw member in normal open position, so as to allow the work to be disposed between the jaws. Movement of the handle in 10 a downward direction will cause the jaw members to move toward each other and in gripping engagement with the work as shown in Figure 3, and as the outer end portion of the jaw 9 is directed upwardly, the part worked upon cannot possibly slip from between the jaws. When 15 the handle is moved in an opposite direction the jaws are moved to their normal position thereby releasing the part worked upon.

It is thought from the foregoing description 20 that the advantages and novel features of my invention will be readily apparent.

I desire it to be understood that I may make 25 changes in the construction and in the combination and arrangement of the several parts, provided that such changes fall within the scope of the appended claim.

What I claim is:

A wrench of the character described compris-

ing a handle, spaced upwardly directed parallel arranged arms formed with one end of said handle and constituting a stationary jaw having curved toothed surfaces on the lower portions of the arms thereof with the teeth directed toward the handle, a movable jaw member including a shank pivotally secured between the arms of the stationary jaw member adjacent to the upper and outer ends thereof, a toothed jaw formed with the free end of the shank and having an upwardly extending outer end portion directed toward the outer end of the stationary jaw, said shank being slightly curved from its connection with its jaw and curved to a greater degree from 80 its pivot point to dispose the jaw thereof in co-operation with the stationary jaw, the teeth of the movable jaw being directed in the direction opposite from that of the teeth of the stationary jaw, said handle having a recess at the juncture of the spaced arms therewith and spring means having one end slotted and secured in the recess and its opposite end rolled upon itself and engaging the upper surface of the shank adjacent its pivot point for holding the movable jaw member in normal open position. 85 90 95 100
